(57) **CLAIM**

The ornamental design for a semiconductor element, as shown and described.

DESCRIPTION

FIG. 1 is a front elevational view showing a semiconductor element according to the present invention;

FIG. 2 is a rear elevational view of the element of FIG. 1;

FIG. 3 is a top plan view of the element of FIG. 1;

FIG. 4 is a bottom plan view of the element of FIG. 1;

FIG. 5 is a right side elevational view of the element of FIG. 1, the left side elevational view being a mirror image of the right side elevational view; and,

FIG. 6 is a top front perspective view of the element of FIG. 1.
